(57) **CLAIM**

The ornamental design for an adapter for impact rotary tool, as shown.

DESCRIPTION

FIG. 1 shows a perspective view of the present design.

FIG. 2 shows a right side elevational view of the present design.

FIG. 3 shows a front elevational view of the present design; and,

FIG. 4 shows a left side elevational view of the present design.

1 Claim, 2 Drawing SheetsFIG. 1

FIG. 2

FIG. 4

FIG. 3
